UNITED STATES PATENT OFFICE.

EMILE RUMPP, OF PHILADELPHIA, PENNSYLVANIA, ASSIGNOR TO WILLIAM H. HORSTMANN COMPANY, OF PHILADELPHIA, PENNSYLVANIA, A CORPORATION OF PENNSYLVANIA.

DESIGN FOR WOVEN FRINGE.

40,247.

Specification for Design.

Patented Aug. 31, 1909.

Application filed June 19, 1909. Serial No. 503,255. Term of patent 3½ years.

To all whom it may concern:

Be it known that I, EMILE RUMPP, a citizen of the United States, residing in Philadelphia, Pennsylvania, have invented a new, original, and ornamental Design for Woven Fringe, of which the following is a specification.

The figure in the accompanying drawing represents a face view of sufficient of a strip of fringe to represent the design, the latter

being repeated as many times as may be necessary in order to produce a strip of the desired length.

I claim:

The ornamental design for woven fringe, as shown.
